UNITED STATES PATENT OFFICE

OTTO KARL QUAST, OF SPOKANE, WASHINGTON

PNEUMATIC AIRCRAFT-PROPELLING MEANS

Application filed October 29, 1929. Serial No. 403,189.

My invention relates to pneumatic aircraft propelling means and the principal objects of the invention are to provide, in combination with air-craft, a plurality of novel propellers comprising vacuum means for drawing air therein from above with considerable force whereby a vertical or upward lift is exerted on said air-craft, and means for discharging said air through the wings of the air-craft at great velocity against the surrounding air whereby the said air-craft is projected through space. Further objects of the invention are to provide, in combination with the propelling means, an air-craft of novel body and wing construction together with other novel details and arrangements as hereinafter set forth.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:

Figure 1 is a top plan view of an air-craft showing in outline the general arrangement of the invention;

Fig. 2 is a view in side elevation of the same;

Fig. 3 is a view in front end elevation;

Fig. 4 is a view in transverse vertical section taken substantially on a broken line 4, 4 of Fig. 1;

Fig. 5 is a view in vertical section showing one of the propellers and taken on a broken line 5, 5 of Fig. 7 with the outer sleeve and housing removed;

Fig. 6 is a similar view with the outer sleeve and housing intact;

Fig. 7 is a view in vertical section of one of the propeller devices taken on a broken line 7, 7 of Fig. 6;

Fig. 8 is a fragmentary plan view showing air intake ports; and

Fig. 9 is a view in vertical section taken on a broken line 9, 9 of Fig. 8.

Referring to the drawings throughout which like reference numerals designate like parts, the numeral 5 indicates the main body of the air-craft which is round in cross section and which tapers from a semi-globular head to a pointed tail which is provided with the usual steering vanes. At the forward end of said body I prefer to provide an upper gill wing 6 and a corresponding lower wing 7. Said wings are relatively small and may have a slight upward inclination whereby they will assist in lifting the forward or heavier end of the air-craft body in its passage through the air as will be understood.

The numeral 8 designates the main body wing of the air-craft which extends correspondingly on both sides of the main body 5 and a greater portion thereof. Said wing converges toward the rear end of the air-craft and its outer or side edge portions are provided with a plurality of corresponding steps 9 for reasons presently set forth.

It may here be stated that the primary feature of my invention resides in its mode of propulsion which consists essentially in drawing air into the device and discharging same at a very high velocity. In the embodiment of this feature a plurality of air propeller mechanisms designated as a whole by the numeral 10 are disposed within the air-craft body 5. Ordinarily one of such propellers is provided for each oppositely disposed pair of wing steps 9 and one for each of the gill wings 6 and 7. An air intake 11 extends downwardly through the body 5 to each of said propellers and an exhaust conduit 12 extends through the wing 8 to the wing steps 9 where it is flared or enlarged, as at 13, whereby the air expands as it is discharged therefrom. Said air intakes may extend from a forward direction to the propellers located in the forward end of the air-craft body and the exhaust conduits extend

to the rear edge portions of the gill wings 6 and 7. Thus the air sucked into the propellers from above will have a lifting effect on the air-craft while its discharge therefrom in a rear direction against the surrounding outside air at great velocity will drive the air-craft ahead.

The propeller devices 10 which furnish the motive power for the air-craft comprise a shaft 14 to one end of which is fixed a pulley 15 whereby power may be applied from any desired and suitable source. Said shaft is mounted in bearings 16 on the sides of a stationary cylindrical housing comprising an inner drum 17 disposed in eccentric relation with said shaft and an outer drum 18 integral with said inner drum and in concentric relation with the shaft.

A cylindrical rotor member 19 has four integral radial wings 20, dividing said rotor into four equal parts, that are secured to a central hub 21 which is keyed to the shaft 14. Each of said wings is correspondingly recessed or slotted from its outer end to receive vanes 22 that are slidably disposed within said slots. The exterior edge portion of said vanes has an antifriction roller 23 mounted therein and said rollers are adapted to engage the interior cylindrical wall of the inner drum 17. Each of said vanes is provided on its inner edge with a pair of pins 24 fixed thereto and slidably disposed within holes in the wings 20. A spring 25 is located in the bottom of each of said holes and normally in compression against the ends of said pins whereby the vanes will be impelled outwardly thus keeping the anti-friction rollers in continuous engagement with said inner drum as will be understood.

Entry ports 26 are provided in the top of the cylindrical housing through the drums 17 and 18 that register with the intake 11. An exhaust pipe 27 extends from the inner drum 17 to a communication with the exhaust conduit 12. Thus when the rotor member 19 is rotating in a clockwise direction, as indicated by the arrow in Fig. 6, the vanes 22 will trap the air entering through the top intake and carry it around in the eccentric chamber between said rotor and the inner drum 17 and force it out through the exhaust whereby it is discharged through the expanded outlets 13 at considerable velocity.

A rotary casing or sleeve 28 fits snugly around the outer drum 18 of the stationary housing and its end is keyed or otherwise fixed to the shaft 14 at 29. Said casing revolves with said shaft and around said stationary housing and is provided with a plurality of spaced slots 30 that correspond with the entry ports 26. Said slots are four in number and are positioned to register with said entry port slightly in advance of each of the vanes 22 and to close said port an instant ahead of the time that said vanes reach the en-

try port. A vacuum will thus be formed behind each vane as it passes said port which vacuum will be maintained until the next slot in said rotary casing reaches the entry port at which instant the air will be sucked into the drum from above with considerable force which will tend to lift the air-craft.

It will now be apparent that I have provided efficient pneumatic means for simultaneously lifting and propelling air-craft and it will be understood that the several propeller mechanisms are so timed as to alternately reach the intake and exhaust strokes whereby their impulses will be smooth and continuous in the operation of the device as a whole.

Having thus described my invention, it being understood that minor changes may be resorted to in its construction without departing from its scope and spirit, what I claim and desire to secure by Letters Patent of the United States is:—

1. The combination of an air-craft having a round body tapering from a semi-globular head to a pointed tail, relatively small upper and lower gill wings adjacent said head, a relatively large wing extending a greater portion of the body, steps forming the outer edges of said wing, a plurality of rotary propelling mechanisms mounted within the body, vacuum means for forcibly drawing air from above into said mechanisms, discharge means for forcibly expelling the air rearwardly through the steps of the large wing, and intake and discharge means for the propelling mechanisms of the gill wings.

2. The combination with an air-craft of pneumatic air-craft propelling means consisting of a plurality of power driven propelling mechanisms each comprising a stationary cylindrical housing having an inner and an outer drum, a shaft concentric with the outer drum and eccentric with the inner drum, a cylindrical rotor member for said shaft within the inner drum, radial wings for the rotor, a spring impelled vane for each rotor wing arranged to engage the inner wall of the inner drum, an entry port above the propelling mechanism and in communication with the inner drum, an exhaust conduit extending from the inner drum to outlets in the wings of the air-craft, a sleeve for the cylindrical housing fixed to the shaft and having spaced slots adapted to register with the air entry port, and said slots arranged to open and close said entry port slightly in advance of each of said vanes.

3. The combination with an air-craft of pneumatic air-craft propelling means consisting of a plurality of power driven propelling mechanisms each comprising a stationary cylindrical housing having an inner and an outer drum, a shaft concentric with the outer drum and eccentric with the inner drum, a cylindrical rotor member for said shaft within the inner drum, radial wings for the rotor,

a spring impelled vane for each rotor wing arranged to engage the inner wall of the inner drum, anti-friction rollers for said vanes, an entry port above the propelling mechanism and in communication with the inner drum, an exhaust conduit extending from the inner drum to outlets in the wings of the air-craft, a sleeve for the cylindrical housing fixed to the shaft and having a plurality of spaced slots adapted to register with the air entry port, and said slots arranged to open and close the entry port slightly in advance of each of said vanes.

In testimony whereof I affix my signature.

15 OTTO KARL QUAST.
